DESIGN FOR A HUBCAP TOOL

William H. Otto, San Francisco, Calif.

Application January 12, 1943, Serial No. 109,243

Term of patent 14 years

To all whom it may concern:

Be it known that I, William H. Otto, a citizen of the United States of America, residing in the city and county of San Francisco, State of California, have invented a new, original, and ornamental, Design for a Hubcap Tool, of which the following is a specification, reference being had to the accompanying drawing forming part thereof.

The drawing is a perspective view of a tool

showing my new design, including a base or strut member from the center of which extends an elongated hook, and with a handle projecting substantially at right angles to both the strut and hook.

I claim:

The ornamental design for a hubcap tool, as shown and described.

WILLIAM H. OTTO.
